UNITED STATES PATENT OFFICE.

JOHN F. O'CONNOR, OF CHICAGO, ILLINOIS, ASSIGNOR TO W. H. MINER COMPANY, OF CHICAGO, ILLINOIS, A CORPORATION OF ILLINOIS.

ANTIFRICTION-BEARING FOR RAILWAY-CARS OR OTHER VEHICLES.

No. 909,108.

Specification of Letters Patent.

Patented Jan. 5, 1909.

Application filed May 8, 1908. Serial No. 431,862.

To all whom it may concern:

Be it known that I, JOHN F. O'CONNOR, a citizen of the United States, residing in Chicago, in the county of Cook and State of Illinois, have invented a new and useful Improvement in Antifriction Center-Bearings for Railway-Cars or other Vehicles, of which the following is a specification.

My invention relates to anti-friction center 10 bearings for railway cars or other vehicles.

In anti-friction center bearings for railway cars of the kind heretofore commonly in use, great difficulty and inefficient operation is experienced under the enormous load of the 15 modern large heavy cars, owing to the fact that the anti-friction rollers do not materially reduce the friction between the rims of the center plates under the side thrust of the train when rounding curves.

20 The object of my invention is to provide an anti-friction center bearing of a simple, strong and durable construction, by means of which the difficulties or objections heretofore experienced may be practically over- 25 come without occasioning other objections or difficulties.

My invention consists in the means I have discovered and employ for accomplishing this object or result. That is to say, it consists in upper and lower bearing plates provided each with a plurality of opposing or oppositely inclined annular treads and a plurality of separate series or sets of anti-friction rollers traveling on said annular 35 treads, and interposed between the upper and lower center plates, so that the axes of one set of rollers are inwardly and downwardly inclined, while the axes of another set of rollers are inwardly and upwardly inclined, in order that the several sets of rollers in connection with such oppositely inclined annular treads will thus cause the rollers themselves to resist the side thrust action of the train in rounding curves upon the center 45 plates.

My invention further consists in the novel construction of parts and devices and in the novel combinations of parts and devices herein shown and described.

50 In the accompanying drawing forming a part of this specification, Figure 1 is an elevation of a device embodying my invention. Fig. 2 is a central vertical section through the center plates on line 2—2 of Fig. 1. Fig. 3 is a plan view partly broken away.

In the drawing, A represents the truck bolster and A' the body bolster of a railway car or other vehicle.

B is the lower or truck center plate, C C' C² anti-friction rollers, D the upper center 60 plate and F F' loose rings interposed between the several series of anti-friction rollers C C' C².

The lower center plate B has an annular hub b and an annular rim b¹, and it is provided preferably with two opposing or oppositely inclined annular treads b² b³ and an intermediate annular tread b⁴ for the anti-friction rollers to travel upon.

The upper center plate D has a central 70 stud or hub d and an annular rim d¹, and it is provided with two opposing or oppositely inclined annular treads d² d³ and an intermediate annular tread d⁴.

The rollers C C' C² are each preferably furnished with rounded ends c to bear against the upright faces of the separating rings F F' and of the annular rim b¹ and hub b of the lower center plate.

The lower center plate B is provided with 80 a recess or enlargement b⁵ to receive the connecting ring G which is secured to the hub or stud d of the upper bearing plate D after the bearing plates B D are assembled. The connecting ring G is preferably thus secured 85 in place by a flange or lip d⁵ on the stud or hub d of the upper center plate B, which is clenched or bent over the connecting ring G.

As the inner set or series of rollers C have their axes downwardly and inwardly inclined, while the outer set of rollers C² have their axes oppositely inclined or inwardly and upwardly inclined, the two opposing sets of rollers C C' effectually operate to resist the side thrust action of the train upon the center plates, and thus to prevent any material friction between the center plates due to the side thrust of the train, while at the same time the inner and outer sets of rollers C C' in connection with the intermediate set C² 100 effectually operate to prevent material friction between the center plates under the weight or downward load of the car thereon.

I claim:

1. The combination with upper and lower 105 center plates, each furnished with a plurality of differently inclined annular treads of a plurality of separate and oppositely inclined sets or series of anti-friction rollers between the center plates, substantially as specified. 110

2. The combination with upper and lower center plates, having interfitting annular hubs and annular rims and each provided with oppositely inclined annular treads, of 5 two sets of oppositely inclined anti-friction rollers, substantially as specified.
3. The combination with upper and lower center plates, having interfitting annular hubs and annular rims and each provided 10 with oppositely inclined annular treads, of two sets of oppositely inclined anti-friction rollers, and an intermediate set of anti-friction rollers between said oppositely inclined sets, substantially as specified.
- 15 4. The combination with upper and lower center plates having interfitting annular hubs and annular rims, and each provided with oppositely inclined annular treads, of two sets of oppositely inclined anti-friction 20 rollers, and a separating ring between said sets of rollers, substantially as specified.
5. The combination with upper and lower center plates having interfitting annular hubs and annular rims, and each provided with oppositely inclined annular treads, of 25 two sets of oppositely inclined anti-friction rollers, and an intermediate set of anti-friction rollers between said oppositely inclined sets, and separating rings between the several sets of anti-friction rollers, substantially as specified.
6. The combination with upper and lower bearing plates, each having a plurality of oppositely inclined annular treads of a plurality of sets of anti-friction rollers between 30 35 said bearing plates, the rollers of the one set being oppositely inclined from those of the other substantially as specified.

JOHN F. O'CONNOR.
